UNITED STATES PATENT OFFICE

156,722

BOTTLE

Ranzy Mary Gammal, Braintree, Mass.

Application February 26, 1947, Serial No. 137,176

Term of patent 3½ years

(Cl. D58—6)

To all whom it may concern:

Be it known that I, Ranzy Mary Gammal, a citizen of the United States, residing at Braintree, in the county of Norfolk and State of Massachusetts, have invented a new, original, and ornamental Design for a Bottle, of which the following is a specification, reference being had to the accompanying drawing, forming part thereof.

The figure is a perspective view of a bottle, showing my new design.

The characteristic feature of my design is the sequined covered cap in combination with a sequined covered heart-shaped pendant all as shown in the drawing.

I claim:

The ornamental design for a bottle, as shown and described.

RANZY MARY GAMMAL.
